AUTOMATIC COUPLER FOR MINE CARS

Church G. Humphreys, Volant, Pa., assignor of
one-fourth to Frank Barczyk, Volant, Pa.

Application July 29, 1940, Serial No. 348,194

3 Claims. (Cl. 213—178)

My invention relates to new and useful improvements in car couplers.

An important object of my invention is to provide an efficient and efficacious coupler which may be easily applied to a car and which is particularly adapted to be applied to mining and like cars which are operated under conditions where it is often necessary to couple adjacent cars when the same are disposed on a sharply curved portion of the track.

Another object of my invention is to provide a coupler which is uniquely constructed so as to be automatically placed in coupling position regardless of the angular relation of the bumpers of the cars to be coupled.

Still another object of my invention is to provide a coupler of the above-mentioned character which includes means for locking the coupler in position and means for manually simultaneously releasing the locking means and uncoupling the said cars.

Other objects and advantages of my invention, will be apparent during the course of the following description.

In the drawing, forming a part of this specification, and wherein like numerals are employed to designate like parts throughout the same,

Figure 1 is a plan view illustrating fragmentary portions of the adjacent mining cars, which portions are provided with a coupling means embodying my invention.

Figure 2 is a longitudinal sectional view taken on the line 2—2 of Figure 1, and showing parts in section and parts in elevation, and

Figure 3 is a fragmentary perspective view of the coupling lug and supporting bumper embodying a part of my invention.

In the accompanying drawing, wherein for the purpose of illustration is shown a preferred embodiment of my invention, the numerals 10 and 11 designate bumpers carried by and extending longitudinally of adjoining cars, fragmentary portions of which cars are shown at 12 and 13. The bumper 10 is here illustrated as extending forwardly of the car 12 and the bumper 11 is illustrated as extending rearwardly of the car 13, the bumpers being attached to either the body of the car or to the supporting framework thereof.

The coupling lug 14 is mounted on the longitudinal axis of the bumper 11 and is in the form of an upstanding block, the outer or front edge of which is arranged flush with the outer edge 20 of the bumper. The edge 20 is arcuately curved in plan to provide a convex bumper face and the lug 14 is formed on an attaching plate 15 that

is bolted to the upper face of the bumper 11. The lug is substantially square in plan except for the outer edge thereof which, together with the corresponding edge of the plate 15, is shaped to follow the shape of the edge 20 of the bumper. In side elevation the lug is of substantially triangular formation and the inclined front face 16 of the lug slopes from the outer edge of the bumper to the upper edge of the vertical rear wall 17 and the side faces 18 and 19 thereof incline from the side edges of the lug to substantially the longitudinal center thereof. Each of the front and side faces provides a surface adapted to be engaged by the complementary movable part 15 of the coupler, which movable part projects forwardly of the car to be coupled and rides along one of the faces in a manner to be automatically disposed in coupling relation therewith.

The bumper 10 carries the mentioned complementary movable part of the coupler. A wear plate 21 comprises a U-shaped metallic member the end web 22 of which is arcuately curved to conform to the forward edge 23 of the bumper and the upper and lower sides 24 and 25 of the plate are disposed in embracing relation therewith. The sides are received within recesses cut into the upper and lower faces of the bumper so that the outer surfaces of the wear plate will extend in contiguous relation to the upper and lower faces of the bumper. A clevis 26 of substantially the same width as the wear plate and bumper is pivoted to the wear plate at substantially its middle by the pin 27. The end web 28 of the clevis is arcuately curved in plan and the radius 35 of the curve is substantially greater than the radius of the end web 22 whereby the middle of the web 28 will engage the wear plate and the portions of the clevis web arranged at opposite sides thereof will extend in angularly spaced relation with the corresponding portions of the wear plate. The upper and lower flanges 29 and 30 of the clevis embrace the wear plate so that friction developed between these parts by pivoting of the clevis about the pin 27 will not effect wear on any parts of the bumper.

The latch 31 includes a supporting member 32 which is provided with a shank 33 riveted, or otherwise secured, to the top flange 29 of the clevis. The pin 27 extends upwardly through aligning openings in the clevis, wear plate and bumper and the extending end thereof is received by an aligning opening in the member 32, the retaining nut 34 being threaded thereon to support the said member as it pivots about the pin with the clevis. The portion of the shank 33 ex-

tending forwardly of the pivot pin is formed with an eyelet 35 which receives the bail portion 36 of the ring 37. The bail is formed at opposite sides of the eyelet with radial flanges 38 which engage the sides of the eyelet to prevent lateral movement of the bail. The portion of the bail extending through the eyelet, however, constitutes a journal which permits the ring to have an independent vertical movement relative to the clevis. The bar 39 underlies the ring forwardly of the eyelet and normally holds the ring in a horizontal position, the bar being carried by and movable with the clevis so that the ring may be freely swingable laterally with the clevis without disengagement of the same from the bar.

As clearly illustrated in Figure 2, the bumpers 10 and 11 on the opposite ends of the cars are arranged in horizontal alignment whereby movement of the bumper 10 in the direction of the bumper 11 will cause the foremost portion of the ring 37 to engage the inclined front face of the lug 14. Continued advancement of the bumper 10 will cause the ring to ride upwardly on the face until it extends beyond the rear wall 17, at which time it will drop into coupling engagement with the lug as illustrated by the full lines in Figure 2. The coupling of the cars may be effected in the above manner when they are arranged in longitudinal alignment with each other; however, it is frequently necessary that the cars be coupled when the cars are riding upon a sharply curved portion of the track. Under these conditions the longitudinal axes of the cars are disposed in angular relation with each other and, if the clevis 26 is in a neutral or central position with the ring 37 extending directly forwardly thereof, the ring will approach the coupling lug at one side thereof and fail to engage therewith.

I have, therefore, provided an arrangement for automatically positioning the ring in coupling relation with the lug regardless of the angular relation of the cars to be coupled with each other. If the angle between the cars is such that the ring 37 fails to properly engage or contact the lug 14, the ring will pass beyond the lug and edge 20 of the bumper 11 will engage the adjacent end wall of the clevis 26. Continued advancement of the bumper will, therefore, cause the clevis to pivot about the pin 27 and the ring 37 will be moved laterally with the clevis. The lateral swinging of the ring will cause the same to engage the confronting side face 18 or 19 as the case may be and, as the clevis continues to pivot, the ring will be caused to ride upwardly on the contacted face and to drop behind the rear wall 17 in latching association with the lug.

Obviously, it is immaterial from which side the bumper 10 approaches the bumper 11. If it approaches from the right, as illustrated in Figure 1, the ring will project laterally of the face 18 and engagement of the clevis with the outer edge of the bumper 11 will move the clevis to the dotted line position to cause the ring to ride upwardly on the face 18. Conversely, if the bumper 10 approaches from the left, the ring will project laterally of the face 19 and engagement of the clevis with the edge of the bumper 11 will cause the ring to be swung laterally about the pin 27 whereby it will ride upwardly on the face 19.

Any suitable latching arrangement may be provided for retaining the ring in latched association with the lug 14. I have here illustrated the latching means as comprising an upstanding support 40 spaced rearwardly of the wall 17 of the lug 14. An actuator bar 41 is carried for

vertical sliding movement by the support and the lower end thereof is formed with a right angularly extending foot portion 42 normally received within a slot 43 in the bumper 11 and extending from the rearward end of the lug 14 to adjacent the rearward end of the bumper 11. A supporting bracket 44 is positioned rearwardly of the bar 41 and the lug 45 extending from the rearward edge of the bar engages the upper edge of the bracket to limit the downward movement of the bar.

The latch element 46 includes arms 47 pivoted to the support 40 by the pin 48. The arms extend forwardly and downwardly from the pivot at an angle substantially equal to the angular rear face 16 of the lug 14 whereby the arms will comprise, in effect, upward continuations of the face. The horizontal arms 49 integrally connect with the downwardly inclined arms 47 in slightly rearwardly spaced relation with the lug 14, which horizontal arms extend in embracing relation to the support where they are joined by a transverse member 50 which bears against and is supported by the lug 45.

The latch mechanism is provided with a manual release which comprises an arm 51, the middle portion 52 of which is journaled within the bearing 53 carried by the rearward end of the car 13. The portion 52 is adapted to rotate about a horizontal axis and the end 54 thereof extends forwardly at one side of the bearing and terminates in an eyelet 55 which pivotally receives the ring 56. The ring passes through an opening in the upper end of the bar 41 so that when the downwardly bent end 51 of the rod is moved upwardly, the arm 54 will be caused to swing upwardly and to elevate the bar 41. As the bar is caused to rise, the lug 45 will raise the transverse member 50 of the latch element and cause the inclined arm portions 47 thereof to be swung downwardly about the pivot 48. After the arms have begun their downward pivotal movement to provide a substantial space between the latch element and the rear wall 17 of the lug 14, the foot 42 of the bar will engage the portion of the ring 37 extending rearwardly of the lug. When the bar is raised to the dotted line position illustrated in Figure 2 the ring will be positioned above the lug 14 to release the coupling connection between the cars.

It is obvious that, when the cars are being coupled together, the ring may ride upwardly on any of the inclined faces 16, 18 and 19 of the lug and that as the same moves to a position rearwardly of the lug it will rest upon the forwardly extending arms 47 of the latch elements. The ring is substantially heavier than the latch element in a manner whereby it will overbalance the same and be permitted to drop into locked engagement therewith.

It is to be understood that the form of my invention, herewith shown and described, is to be taken as a preferred example of the same, and that various changes in the size, shape and arrangement of parts may be resorted to without departing from the spirit of my invention, or scope of the appended claims.

Having thus described my invention, I claim:

1. In a coupler for joining two cars, each of which cars is provided with extending bumpers formed with convex meeting ends, an upstanding coupling lug mounted on one of the said bumpers, said lug having an inclined end wall and upwardly convergent side walls, a clevis mounted for pivotal movement about a vertical axis on the

other of the said bumpers and having an arcuately curved end wall of substantially greater radius than the end wall of the bumper on which it is mounted, catch means for engaging the said lug fixedly mounted on the clevis and movable therewith but having a portion which is independently swingable about a horizontal axis and which portion normally projects beyond the bumper on which it is mounted, the end wall of the clevis being engageable with the end of the bumper carrying the coupling lug when the bumpers approach each other to pivot the vertically swingable portion of the catch means into register with the said lug whereby the said catch means may move into locked engagement with the lug by traversing the end wall thereof when the bumpers are in substantial alignment or by traversing either of the side walls of the lug when the bumpers are in angular relation.

2. In a coupler for joining two cars provided with bumpers extending therefrom and having convex meeting end walls, a lug fixed to one of said bumpers and having upwardly inclined front and side walls and a vertical rear wall, a clevis pivotally mounted on the other bumper about a vertical axis and having an arcuately curved front end wall formed on a greater radius than that of the end wall of the bumper on which it is mounted, catch means fixedly mounted on the clevis to be carried thereby, and a vertically movable ring included in the catch means and normally projecting outwardly from the bumper

5 upon which the clevis is mounted to traverse either of the inclined walls of the lug to lock the ring to said lug when the lug carried bumper contacts the clevis.

3. In a coupler for joining two cars provided with bumpers extending therefrom and having convex meeting end walls, an upstanding coupling lug fixed to one of said bumpers, said lug having an inclined front wall, a vertical rear wall and upwardly convergent side walls, a clevis mounted for pivotal movement about a vertical axis on the other bumper and having an arcuate curved end wall formed on a greater radius than that of the end wall of the bumper on which the clevis is mounted, a coupling ring fixed to said clevis to be carried thereby, said coupling ring being independently swingable about a horizontal axis and normally projecting outwardly from the bumper upon which the clevis is mounted for disposal about said lug to lock the ring thereto, whereby the cars may be coupled when the longitudinal axes of the bumpers are in alignment by movement of the coupling ring along the inclined front wall of the lug, and whereby the cars may be coupled when the axes of the bumpers are disposed in angular relation by reason of the fact that one side of the end wall of the clevis will be first engaged by the arcuate end of the lug carried bumper to pivot the clevis for causing said ring to traverse one of the convergent side walls of the lug.

CHURCH G. HUMPHREYS.
